UNITED STATES PATENT OFFICE.

FREDERICK S. McCULLOUGH, OF CLEVELAND, OHIO, ASSIGNOR TO GLENN L. MARTIN,
OF CLEVELAND, OHIO.

RADIOTELEGRAPHY.

Application filed July 7, 1919. Serial No. 308,978.

To all whom it may concern:

Be it known that I, FREDERICK S. McCULLOUGH, a citizen of the United States, resident of Cleveland, county of Cuyahoga, and 5 State of Ohio, have invented new and useful Improvements in Radiotelegraphy, of which the following is a specification, the principle of the invention being herein explained and the best mode in which I have 10 contemplated applying that principle, so as to distinguish it from other inventions.

My invention relates to systems of radio telegraphy, and more particularly to systems at receiving stations for determining 15 the direction of incoming electro-magnetic waves, so that the location of the transmitting station may be ascertained.

In the directional systems hitherto used, there have been employed large loops or 20 coils of wire for the receiving antenna, these loops being usually flat coils wound on a square frame having sides of several feet or several yards in length. While directional loops of such size are satisfactory for permanent land stations, it can be readily seen 25 that there are grave objections to them for portable stations such as those on a small boat, and more particularly on an airplane. For the latter, it is essential to have the apparatus in as compact form as possible, and by my system I can provide means of 30 extremely small dimensions, which will satisfactorily determine the direction of a transmitting radio station. At the same time, I 35 provide for the detection of the incoming oscillations.

My receiving elements comprise coils enclosed in an evacuated tube, together with such other elements as are necessary to carry out my invention, as will appear more 40 particularly from the detailed description of my system, together with the drawings.

The annexed drawings and the following description set forth in detail certain means 45 embodying my invention, the disclosed means, however, constituting but one of the various mechanical forms in which the principle of my invention is employed.

In the drawings:

50 Figure 1 shows a general view of the circuits in my system, together with the elements of my invention in diagrammatic form;

55 Figure 2 shows a view of my evacuated tube containing a single unit of coils and fil-

ament, and a diagram of a modified form of my circuits.

Figure 3 shows a view of one of my tubes containing two units of coils and filaments, and a modified form of circuits. 60

Figure 4 shows an arrangement of circuits and elements of my invention where I desire to amplify the received oscillations.

In Figure 1, 1 is a coil having a number of turns enclosed in an evacuated tube and forming one of my receiving elements. 2 represents a second coil also enclosed in the same tube and inductively related to the first coil. 3 represents a filament also enclosed in the evacuated tube. A line is drawn about 70 these three elements to indicate that they are all in one evacuated tube. 4 is a battery for heating the filament 3. 5 is a variable condenser between the coils 1 and 2. 6 is a variable condenser between the coil 2 and the 75 filament 3. 7 is a variable inductance in circuit with the coil 1. 8 is a variable inductance in circuit with the coil 2. 9 is a variable battery by means of which current is sent through the tube from the coil 1, 80 through the coil 2, to the filament 3. The battery 9 need not necessarily be variable, and similar batteries are shown not variable in some of my other figures. 10 is a telephone for indicating changes or signals in 85 the circuit including the tube and the battery 9. 11 is a variable inductance coil in circuit with the filament 3.

In Figure 2, 13 is an evacuated glass tube or vessel, 1 is a coil within the tube, with its terminals passing outside. 2 is another coil inside coil 1, with its terminals passing outside. These coils may be made of nickel or of copper, or of any other suitable material. The return leads from the far ends of the 95 coils to the base of the tube are shown outside the coils, close to the wall of the tube, so as to avoid confusion in the drawing, but in practice they are generally carried back inside one or both coils, covered by small 100 glass tubes, or other suitable insulation. 3 is a filament inside the coil 2, with its terminals passing outside the tube. This filament consists of a heated portion of tungsten or other suitable material, supported by a wire of 105 copper, or of other suitable material. 4 is a battery for supplying current to the filament. 5 is a variable condenser between the coil 1 and the coil 2. 6 is a variable condenser between the coil 2 and the filament 3. 110

9 is a battery which supplies current to the circuit including the coil 1, the filament 3, and the telephone receiver 10. 12 is a variable resistance for regulating the current 5 in the filament.

In Figure 3, 17 is an evacuated tube or vessel, 1 is a coil with terminals leading outside of the tube. 2 is a coil inside the coil 1, with its terminals leading outside of the tube. 3 is a filament inside of coil 2, with its terminals leading outside of the tube. 14 and 15 are coils, and 16 is a filament, similar, respectively, to coils 1 and 2 and the filament 3 just described, and placed in 15 side the same tube with terminals leading outside of the tube. 5 and 6 are variable condensers. 4 is a battery for heating the filament 3, and 12 is a variable resistance. 9 is a battery. 52 is a transformer for trans- 20 ferring the oscillations of the circuit containing battery 9, coil 1 and filament 3 to coil 15 of the second unit, whence they are impressed, in amplified form, upon the circuit including coil 14, filament 16, battery 25 57 and the telephone receiver, or other indicating device 58. 53 is a variable resistance and 54 a battery for heating filament 16. 55 is a variable condenser between coil 14 and coil 15, and 56 is a variable condenser 30 between coil 15 and filament 16. The first unit in this tube is used for receiving the incoming electro-magnetic waves, and the second unit is also used for this purpose and at the same time acts as an amplifier of the os- 35 cillations received by the first unit, by means of the appropriate circuits and connections shown.

In Figure 4, 1 is a coil enclosed in an evacuated tube. 2 is a second coil in the same tube. 3 is a filament also in the tube. 40 4 is a battery supplying current to the filament. 5 is a variable condenser between coil 1 and coil 2. 9 is a variable battery. 12 is a variable resistance for regulating the current in the filament. 18 is a battery for keeping coil 2 electro-negative, and 19 is a variable high resistance across battery 18, which acts as a potentiometer. 20 is a transformer for transferring the oscillations in 45 the circuit comprising coil 1, filament 2, and battery 9, to coil 22 in the next unit. Coil 22 is in an evacuated tube with coil 21 and filament 23. 24 is a battery and 25 a variable resistance. 26 is a battery and 27 a 50 high resistance or potentiometer. 28 is a battery. 29 is a variable condenser between coils 21 and 22. 30 is a transformer for transferring the oscillations in the circuit comprising coil 21, filament 23 and battery 28, to the coil 32 in the next unit or amplifying stage. Coil 32 is in an evacuated tube 55 inside the coil 31 and outside of filament 33, also enclosed therein. 34 is a battery and 35 a variable resistance. 36 is a battery and 37 a potentiometer for keeping coil 32

electro-negative. 38 is a battery. 39 is a variable condenser between coils 31 and 32. 40 is a transformer for transferring oscillations in the circuit containing coil 31, filament 33 and battery 38, to coil 42 in the next 70 unit or amplification stage. Coil 42 is between coil 41 and filament 43 in an evacuated tube. 44 is a battery and 45 a variable resistance. 46 is a battery and 47 a variable high resistance or potentiometer, for 75 the purpose of keeping coil 42 electro-negative. 49 is a variable condenser between coils 41 and 42. 50 is a variable condenser in circuit with the transformer 40 and coil 42. The principal function of condenser 50 80 is to assist in tuning the circuits in this final stage. 48 is a battery for supplying current to the circuit containing coil 41, filament 43, and the sensitive galvanometer 51.

The sensitive galvanometer 51 is one means 85 of indicating the amplified oscillations received, but it may be replaced by other forms of indicator. It involves the principle of indicating by visual means the strength of the oscillations received on directional receivers. This feature is not a 90 part of the present invention, but is separately described and claimed in my application Serial No. 313,161, filed July 25, 1919.

In order that all the coils in all the tubes 95 may contribute to the fullest extent to the directional receiving effect, the coils and the tubes should be so arranged that the axes of the coils are all parallel to each other.

To determine the direction of the incoming electro-magnetic waves, the tube is turned, or when there is more than one, the tubes are turned together, until the maximum sound is heard in the telephone receiver, or the maximum deflection is observed on the galvanometer, or until the maximum effect is obtained with any other indicating means I may employ. It has been found that this maximum effect is produced when the planes of the individual 100 turns of the coil or coils are as nearly as possible in the direction of the transmitting station. As the coils are helical in form, the individual turns do not lie in true planes, but when the axis of each coil is at right angles 105 to the direction of the transmitting station, the average effect is greatest. Instead of the position for maximum effect, the position for minimum effect can be found, which will be at right angles to the former position. The minimum effect position is sometimes more readily determined. I can also arrange my coils in a plane, in the form of a flat spiral, either circular or rectangular, but for mechanical reasons the ordinary 110 helical form of the coils is preferable, especially from the standpoint of tube manufacture.

Taking Figure 1 as an example, the incoming waves affect both the coil 1 and the coil

2, which have a cumulative effect upon each other, and the presence of these incoming waves is detected by means of the electron current flowing from the filament 3 to the coil 1, and the variations in the electric current thereby caused in the circuit through the telephone 10, are indicated by the latter.

The capacitance of this system can be varied at will by means of the condensers 5 and 6, which are outside the tube. The inductance of the system can be increased by increasing the number of turns in the coils 1 and 2, and when it is desirable to have greater inductance than can be obtained with the limitations of space inside the tube, additional inductances outside the tube, such as shown at 7 and 8, can be connected conductively or inductively with the coils in the tube. One means for obtaining this additional outside inductance is to provide coils outside of the tube in inductive relation to those inside and placed as close to them as possible. By means of this variable capacitance and inductance, the system can be tuned to any desired frequency or wave length.

By properly choosing the values of my electrical quantities and proportioning my elements, I can secure regenerative effects in my system, which increase the strength of the received oscillation.

The outside inductance should not be so great as to interfere with the proper resonance effects of the interior elements, and, in general, the inductances, the capacitances and the other electrical features of the whole system should have such values and should be so proportioned that the best effects are produced. These values and proportions I can determine for each system.

In the form of my invention shown in Figure 3, two receiving and detecting units are placed in the same tube, and one of them amplifies the oscillations received by the other, and at the same time assists in obtaining the directional effect.

Additional tubes can also be provided, either for increasing the inductance, or for amplifying the received oscillations, or for both, as shown in Figure 4.

The tube containing my receiving elements need not be more than one inch in diameter, nor more than three inches long, but I do not

limit myself to any particular size. With this system of mine, it is not necessary to have any separate antennæ, and the elements in my tube constitute a means for detecting the received electrical oscillations, as well as for determining the direction of the incoming electro-magnetic waves.

It will be seen from the above description that my system provides an extremely compact means for determining the direction of a radio transmitting station, and is especially applicable to airplanes or small craft, and can even be used in a portable set which can be carried on one's person.

I do not confine myself to the exact constructions and arrangements herein described, but may also employ other means well known to those skilled in the art, but what I claim and desire to secure by Letters Patent is:

1. A radio receiving system comprising two collector coils and a heated filament, enclosed in an evacuated vessel.

2. In a radio receiver, a circuit including an ionizing means and having a collector coil, and an evacuated chamber containing said ionizing means and said coil.

3. A radio receiving system including a source of ionization, a collector coil surrounding said source, and a second collector coil surrounding said first coil, the axes of both coils being parallel, said source and said coils being enclosed in an evacuated vessel.

4. A radio receiving system, including a source of ionization, a collector coil surrounding said source, and a second collector coil surrounding said first coil, said coils having a common axis, said source and said coils being enclosed in an evacuated vessel.

5. In a system of radio transmission, directional receiving means including two collector coils enclosed in an evacuated tube.

6. A radio receiving system comprising two collector coils enclosed in an evacuated vessel, said coils being in inductive relation to each other.

7. In a system of radio transmission, a plurality of receiving elements comprising collector coils in evacuated vessels, said coils having their axes parallel to each other.

Signed by me, this 27th day of June, 1919.
FREDERICK S. McCULLOUGH.
